J. C. RAYMOND.

CIGAR LIGHTER.

APPLICATION FILED SEPT. 14, 1908.

Patented Jan. 19, 1909.

UNITED STATES PATENT OFFICE

JOHN C. RAYMOND, OF BROOKLYN, NEW YORK.

CIGAR-LIGHTER.

No. 910,313.

Specification of Letters Patent.

Patented Jan. 19, 1909.

Application filed September 14, 1908. Serial No. 452,838.

To all whom it may concern:

Be it known that I, JOHN C. RAYMOND, a citizen of the United States, and a resident of Brooklyn, in the county of Kings and State of New York, have made certain new and useful Improvements in Cigar-
Lighters, of which the following is a specification.

This invention is an improvement in cigar lighters and consists in certain novel constructions and combinations of parts as will be hereinafter more fully described and claimed.

In the drawings—Figure 1 is a vertical longitudinal section of a lighter embodying my invention; Fig. 2 is a cross section thereof on about line 2—2 of Fig. 1; Fig. 3 is a top plan view of the device; Fig. 4 is a detail sectional view illustrating the feeding devices for the wick and the cap strip; Fig. 5 is a detail plan view of a portion of such feeding construction; Fig. 6 is a detail perspective view of the trigger; and Fig. 7 is a detail perspective view showing the construction at the igniting end of the cap strip and the wick.

In carrying out my invention I provide a casing A which is made in the form of a pistol and is preferably in two side sections hinged together at A' at one edge and suitably secured by screws or rivets A² at its other edge, so the casing can be conveniently opened to permit access to the interior parts for any desired purpose.

At the grip end of the pistol I provide a cigar cutter B and in said grip end I support the rollers of the wick C and the cap strip D. The wick C is wound in a reservoir E supported in the grip of the pistol and adapted to contain oil or other suitable material which may be absorbed by the wick to increase its inflammable condition. From this reservoir E the wick tube E' extends to a point near the end of the barrel A³ where it is deflected downward at E² so that it discharges to a point at about the center of the barrel A³ as will be understood from Figs. 1 and 2 of the drawing.

The cap strip D which may be of any suitable well known construction extends from its roller forwardly through a tube D' and discharges adjacent to the discharge

end of the wick C as shown in Fig. 2, so it can be operated upon by the hammer F to explode its cap and thus ignite the wick. 55

The hammer F has its rod F' suitably guided at F² in the casing and made in two sections jointed together at F³ so the hammer may rise slightly to permit the readjustment of the pivoted catch G¹⁰, to be presently described, to the position shown in Fig. 1 when the extinguisher is adjusted to the position shown in Fig. 1. 60

The rod F' connects at its rear end with the trigger H which may be operated to advance the hammer, the latter being given its firing stroke by a spring I bearing between the hammer and a plate A⁴ at the front end of the barrel A³ and operating to force the hammer back against the cap strip when the hammer is pushed forward and then released. 65

The trigger H has an upward extension H' operating as a pawl acting upon a ratchet wheel J on a feed shaft K having a feed wheel K' operating to advance the wick C and a wheel K⁴ meshing with a smaller feed wheel K² on a shaft K³, which wheel K² operates to advance the cap strip, it being desired to feed the cap strip more rapidly than the wick as 80 will be understood by those skilled in the art.

Near its front end the barrel is perforated at A⁵ to permit the escape of the flames from the wick and is slotted longitudinally at A⁶ to receive the guiding screws or projections G' 85 on the extinguisher G, the latter being in the form of a cylinder fitting and sliding upon the barrel and pressed normally to the rear against a stop A⁷ by the action of springs G² which bear against the screws or projections 90 G' as shown in Fig. 1. When in the extinguished position shown in Fig. 1, the extinguisher G is held against the tension of its springs G² by means of a catch G¹⁰ pivoted between its ends to the casing, engaging at 95 its lower end in rear of a shoulder G¹¹ on the extinguisher and bearing at its upper end in rear of a shoulder F¹³ on the under side of the hammer-rod.

When the parts are in the position shown 100 in Fig. 1, it will be noticed that if the trigger H be pulled in the usual manner it will advance the hammer and in so doing will move the shoulder F¹³ away from the upper end of the catch G¹⁰, and such catch thus releasing 105 the extinguisher the latter will be forced back

against the strip A⁷ by its springs G². Then when the trigger is released the hammer will be forced back by its spring I to explode a cap and thus ignite the wick, and the flames will 5 pass out of the openings A⁵ which at such time will be unobstructed as the extinguisher will then be in its rearward position.

When it is desired to extinguish the igniter, the tube G may be moved forward by hand 10 against the tension of its springs G² to the position shown in Fig. 1, the catch G¹⁰ dropping to the position shown in Fig. 1, in rear of the shoulder F¹³, the joint F⁸ permitting the readjustment of the parts to the position shown in 15 Fig. 1 as before described.

It will be noticed that the several operations are effected through the manipulation of the trigger except the readjustment of the tube G to the position shown in Fig. 1, which 20 is accomplished by hand.

I claim:

1. The igniting device herein described comprising a casing made in sections hinged together at one edge, means connecting the 25 sections at the other edge, a reservoir in the casing and having a wick tube leading thence, a cap tube in the casing and having its discharge end adjacent to the discharge end of the wick tube, a trigger, feeding means 30 operated by the trigger and having feeding devices operating in connection with the cap tube and the wick tube, a hammer, means for operating the hammer in one direction, a hammer-rod connecting the hammer with 35 the trigger and made in sections, and provided with a shoulder for engagement with an extinguisher catch, the casing having openings or vents for the passage of the 40 flames, an extinguisher movable upon the casing to and from a position covering the flame vents and spring-actuated in one direction, a catch securing the extinguisher over the flame vents, and means on the hammer-rod coöperating with said catch, all substantially as and for the purposes set forth. 45

2. The combination in an igniter with a casing, and a hammer, of a pivoted trigger connected with the hammer, and feeding devices arranged for operation by the trigger 50 whereby to feed a wick and cap strip and

having gearing between the wick and the cap strip, substantially as set forth.

3. The combination with a casing, a hammer and a hammer-rod having a shoulder, of an extinguisher spring actuated in one direction and a catch between the extinguisher and hammer-rod and coöperating with the shoulder on the latter substantially as set forth. 55

4. The combination with a casing having 60 flame vents, of a spring actuated extinguisher sliding to a position over said flame vents, a hammer, an extinguisher catch for holding the extinguisher over the flame vents, said catch being held and released by 65 the hammer substantially as set forth.

5. The combination in an igniter, of a casing having flame vents, a wick tube and a cap tube within the casing, devices for feeding the wick and the cap strip and an extinguisher 70 slidable to and from a position over the flame vents substantially as set forth.

6. An igniter comprising a casing and having a reservoir and a wick tube leading therefrom, a cap strip tube, means for feeding a 75 cap strip and wick, said means comprising drive wheels geared together, a trigger operating said means, means for operating the feed gearing from the trigger and a hammer operated by the trigger substantially as set 80 forth.

7. The combination of a casing having flame vents a sliding extinguisher spring actuated in one direction, a catch for restraining said extinguisher, a hammer and a hammer-rod made in jointed sections and having 85 a shoulder coöperating with the extinguisher catch substantially as set forth.

8. The combination with a cap strip tube and a wick tube having its discharge end deflected, of a hammer-rod having a deflected portion supporting its hammer in position to operate upon a cap strip discharged from its tube and an extinguisher normally inclosing 90 the deflected portion of the wick tube substantially as set forth. 95

JOHN C. RAYMOND.
